EVAPORATING APPARATUS WITH SUPERPOSED COMPARTMENTS AND PROGRESSIVE LEVEL.

1,071,341.

Specification of Letters Patent. Patented Aug. 26, 1913.

Application filed November 6, 1912. Serial No. 729,362.

To all whom it may concern:

Be it known that I, CHARLES LOUIS PRACHE, a citizen of the Republic of France, and resident of Paris, France, have invented new and useful Improvements in Evaporating Apparatus with Superposed Compartments and Progressive Levels, which improvements are fully set forth in the following specification.

10 This invention relates to an evaporating apparatus heated by steam and intended for concentrating liquids, and relates more particularly to a special arrangement for circulating the liquid, the object of which is to 15 increase the transmission of heat through the heating surface.

It is well known that with all the temperature and pressure conditions remaining the same, the transmission of heat in evaporating apparatus depends on the speed of circulation of the steam, on the one hand, and of the boiling liquid submitted to evaporation, on the other hand.

Among the means used for increasing the speed of the liquid, some are well known, such as for instance that which consists in boiling the liquid in tubes heated outside and having a great length relatively to their diameter and incompletely filled with the liquid to be concentrated, in such a manner that in the upper portions of the said tubes, a mixture of steam and liquid is formed, which assumes a great speed of circulation and drives the whole of the liquid contained in the said tubes, the said circulation being obtained merely by the effect of the disengagement of steam.

Experience has shown that the best position to be given to incompletely filled heating tubes, is an inclined position close to the horizontal. Nevertheless, this arrangement has the drawback that the various tubes of the bundle are filled in a different manner, those situated at the top containing less liquid than those situated at the bottom. That fact limits in practice the thickness of the tubular bundles to a small height, and consequently limits also the size of the apparatus that can be built. It has been found 50 moreover that the maximum of evaporation obtained by boiling in an incompletely filled tube, is obtained by keeping the level of the

liquid at a point which is nearer to the upper portion of the tube, the greater the density of the liquid to be concentrated. 55 Thus, with a liquid of small density, such as a weak juice of sugar, the level giving the maximum evaporation, is situated near the lower third of the tube, and when the juice is concentrated to the state of thick syrup, 60 the maximum evaporation takes place when the tube is completely filled.

By means of the arrangement forming the subject of this invention it is possible: 1. To obtain evaporating boilers with slightly inclined tubular bundles, of any desired size. 65 2. To obtain a methodical circulation of the liquid as the density of the product increases, and in such a manner that the mean level of the liquid in the different compartments of the boiler will be the higher, the greater the concentration. 70

A construction of the apparatus according to this invention is illustrated by way of example in the accompanying drawings, in 75 which—

Figure 1 is a longitudinal section parallel to the tubes, Fig. 2 a plan, and Fig. 3 a longitudinal section through the circulation tubes and the discharge tubes. 80

The apparatus comprises a cylindrical or other casing or shell 1 terminating at each end in a tube plate 2 in which are secured the tubes of the bundle 3, the whole of the said bundle being slightly inclined relatively to the horizontal. The space comprised between the two tube plates, the casing and the tubes, forms a chamber for the heating steam, into which chamber steam is admitted through the branch 4, and from 90 which the condensed water escapes through the opening 5. To the bottom tube plate 2 is secured a receiver 6 divided into a certain number of compartments 8 by horizontal partitions 7 forming a joint with the tube 95 plate and dividing the tubes of the bundle into a certain number of superposed horizontal layers. The upper compartment is provided with a branch 9 through which is introduced the liquid to be concentrated, and 100 each of the compartments is moreover provided laterally with a branch 10, through which the liquid being concentrated passes into the said compartment.

To the upper tube plate 2 is secured an upper receiver 11 in which the liquid escaping from the tubes of the bundle, is separated from the steam which has been generated in its interior and which has carried the said liquid out of the tubes in question. The upper receiver itself is divided by curved partitions 12 into a number of compartments equal to that of the bottom receiver, in such a manner that the upper tube plate is divided by the said partitions in the same way as the bottom plate is divided by the partitions 7. The curved partitions are bent so as to form troughs 13 which occupy the whole width of the upper receiver and are closed at one end by a solid partition, while at the other end they terminate in a branch 14 which communicates with the corresponding branches 15 provided in the vertical wall of the upper receiver. These branches establish communication between the various troughs and an equal number of outer circulation pipes 16 which thus establish communication between the compartments of the upper receiver and the corresponding compartments of the bottom receiver. Each trough 13 terminates in a partition 17 raised parallel to the tube plate. Various partitions leave between them conduits 18 through which the steam separated from the liquid collected in the trough, escapes into the free space of the upper receiver, in order finally to be discharged outside through the branch 19. On each of the outer circulation pipes 16, is arranged a level regulator 20 designed in the form of an overflow which admits into the circulation tube of the compartment arranged immediately below, all the liquid escaping through the said overflow. This regulator can be constituted, as shown by way of example in Fig. 3, by a circular branch 21 disposed vertically on the circulation tube, in the center of which branches is arranged a tube 22 also vertical, of a smaller diameter and communicating at the bottom portion by means of the pipe 23, with the circulation tube placed immediately below. The level regulator of the last bottom circulation tube is provided with a branch 24 for the escape of the concentrated liquid from the boiler.

In order to start the boiler, first of all the various compartments are filled with liquid. To that end, the liquid is admitted through the branch 9 into the upper compartment. When the liquid in the first compartment reaches the level 25 determined by the upper portion of the tube 22 forming an overflow for the level regulator 20, the liquid escapes through the tube 22 into the circulation tube 16 of the second compartment situated immediately below, and fills that compartment up to the level 26 determined by the position of the over-

flow 28 of the level regulator of the said compartment. The liquid thus escapes successively into the various compartments and fills them all up to the levels 28, 29, 30 determined by the overflows of corresponding level regulators. When the liquid escapes through the discharge branch 24, all the compartments having been filled, heating steam is admitted through the branch 4, condenses around the tubes of the various layers of the bundle and escapes through the pipe 5 as water of condensation. Under that influence, the liquid begins to boil in all the tubes of the boiler. This boiling produces in each compartment the following circulation.

Under the influence of boiling, the liquid is projected out of each tube of the bundle, mixed with the steam generated, and passes into the upper receiver 11. Steam is separated, and discharged through the branch 19, while the liquid collects in the trough 13 in order to escape through the branch 14 (Fig. 2) into the circulation tube 19 which brings it back, through the branch 10, into the upper compartment of the bottom receiver. The same circulation is produced by boiling in each of the superposed compartments of the boiler.

The liquid to be concentrated being introduced in a continuous manner through the branch 9 into the upper compartment, it follows that a certain quantity of partly concentrated liquid, circulating in the upper compartment, tends to pass over the overflow 22 of the level regulator 20 and escape into the second compartment through the branch 23. This portion of liquid is caused to circulate in a circulation movement in the second compartment, and under the influence of such circulation a certain quantity of liquid which is being concentrated in the second compartment, passes through the corresponding overflow into the third compartment. The same thing takes place between the third and the fourth compartments, up to the last.

The concentrated liquid escaping in a continuous manner through the branch 24, it follows from this general movement of circulation from one compartment to the next that, owing to the evaporation, the density gradually increases in all the compartments, from the upper compartment where it is a minimum, to the bottom compartment where it is a maximum.

The various overflows 28, 29 etc. are adjusted so that the mean level of the boiling liquid in each compartment increases in the same way as the concentration, so that the tubes of the upper compartments remain filled to a very slight extent, while those of the bottom compartments are filled to a much greater extent the degree of increase of the various levels from one compartment 130

to the next, varying moreover in accordance with the nature of the liquid to be concentrated.

Claims.

- 5 1. In an evaporating apparatus, the combination of an inclined shell provided with a steam inlet and at each end with a tube plate; a bundle of tubes disposed within said shell and having their ends connected 10 to said plates; receivers connected to the opposite ends of said shell and each divided horizontally into the same number of superposed compartments, one of said receivers being provided with a steam exhaust and 15 the other with an inlet for the liquid to be concentrated; a plurality of superposed, longitudinal circulation tubes located exteriorly of said shell and corresponding in number to the number of said compartments, said circulation tubes having their 20 opposite ends communicating with the corresponding compartments, and means for continuously discharging a portion of the liquid in each circulation tube into the next 25 lower tube.

2. In an evaporating apparatus, the combination of an inclined shell provided with a steam inlet, and at each end with a tube plate; a bundle of tubes disposed within

said shell and having their ends connected 30 to said plates; receivers connected to the opposite ends of said shell and each divided horizontally into the same number of superposed compartments, one of said receivers being provided with a steam exhaust and 35 the other with an inlet for the liquid to be concentrated; a plurality of superposed, longitudinal circulation tubes located exteriorly of said shell and corresponding in number to the number of said compartments 40 and having their opposite ends communicating with the corresponding compartments; and means for continuously discharging a portion of the liquid in each circulation tube into the next lower tube embodying an upstanding discharge branch 45 provided upon each of said tubes toward its lower end and an upstanding overflow branch disposed within the first-named branch and leading into the next lower tube. 50

In testimony whereof I have signed this specification in the presence of two subscribing witnesses.
